The ornamental design for a portable manual pulse generator, as shown and described.

DESCRIPTION

FIG. 1 is a perspective view of my new design for a portable manual pulse generator showing our new design;

FIG. 2 is a front view thereof;

FIG. 3 is a rear view thereof;

FIG. 4 is a top plan view thereof;

FIG. 5 is a bottom view thereof;

FIG. 6 is a right side view thereof; and,

FIG. 7 is a left side view thereof.

In respective drawings, lines other than the shape lines expressed at surface portions are all for specifying the shapes of three-dimensional surfaces.

The broken lines shown in the figures illustrate portions of the portable manual pulse generator and form no part of the claimed design.
